(57) **CLAIM**

We claim the ornamental design for an aerosol generator body, as shown and described.

DESCRIPTION

FIG. 1 is a front top perspective view of an aerosol generator body.

FIG. 2 is a rear bottom perspective view of the aerosol generator body depicted in FIG. 1.

FIG. 3 is a front elevational view of the aerosol generator body depicted in FIG. 1.

FIG. 4 is a rear elevational view of the aerosol generator body depicted in FIG. 1.

FIG. 5 is a left side elevational view of the aerosol generator body depicted in FIG. 1, the right side elevational view being a mirror image thereof.

FIG. 6 is a top plan view of the aerosol generator body depicted in FIG. 1; and,

FIG. 7 is a bottom plan view of the aerosol generator body depicted in FIG. 1.

The broken lines in the drawings depict portions of the aerosol generator that form no part of the claimed design.
